UNITED STATES PATENT OFFICE.

CHARLES BESELER, OF JERSEY CITY, NEW JERSEY.

DESIGN FOR A JET FOR LIME-LIGHTS.

SPECIFICATION forming part of Design No. 25,253, dated March 17, 1896.

Application filed September 27, 1895. Serial No. 563,911. Term of patent 7 years.

To all whom it may concern:

Be it known that I, CHARLES BESELER, of Jersey City, in the county of Hudson and State of New Jersey, have invented and produced 5 a new and original Design for Jets for Lime-Lights, of which the following is a full, clear, and exact specification.

Reference is to be had to the accompanying drawings, forming a part of this specification, 10 in which similar characters of reference indicate corresponding parts in both the figures.

Figure 1 is a perspective view of my design, and Fig. 2 is a plan view of the same.

The leading feature of the design consists in the continuous bend A, which extends from the base portion B first laterally, as at A', then upwardly and forwardly, as at B², to finally terminate in the contracted spout A³. 15

I claim—

The design for jets for lime-lights herein 20 shown and described.

CHARLES BESELER.
